(57) **CLAIM**

The ornamental design for an eating utensil, as shown and described.

DESCRIPTION

FIG. 1 is a front top perspective view of an eating utensil in accordance with the present invention.

FIG. 2 is a front bottom perspective view showing the eating utensil of FIG. 1.

FIG. 3 is a top plan view showing the eating utensil of FIG. 1, with the bottom being a mirror image thereof.

FIG. 4 is a front elevation view showing the eating utensil of FIG. 1, with the rear being a mirror image thereof.

FIG. 5 is a left elevation view showing the eating utensil of FIG. 1.

FIG. 6 is a right elevation view showing the eating utensil of FIG. 1; and,

FIG. 7 is a front, top perspective showing the eating utensil of FIG. 1 in an open configuration.

1 Claim, 4 Drawing Sheets
